UNITED STATES PATENT OFFICE.

FRANKLIN R. WHITE, OF WATERTOWN, CONNECTICUT, ASSIGNOR TO PATENT BUTTON COMPANY, OF WATERBURY, CONNECTICUT, A CORPORATION OF CONNECTICUT.

BUTTON AND STAPLE FEEDING MECHANISM FOR BUTTON-ATTACHING MACHINES.

1,079,968.

Specification of Letters Patent.

Patented Dec. 2, 1913.

Application filed January 3, 1913. Serial No. 739,930.

To all whom it may concern:

Be it known that I, FRANKLIN R. WHITE, a citizen of the United States, and a resident of Watertown, in the county of Litchfield 5 and State of Connecticut, have made and invented certain new and useful Improvements in Button and Staple Feeding Mechanism for Button-Attaching Machines, of which the following is a specification.

10 My invention relates to button and staple feeding mechanism for button attaching machines of the type wherein buttons are attached to a garment by means of a suitable fastener by an upsetting, riveting or similar 15 operation, and the object thereof is to provide certain improvements in and relating to various of the elements which collectively form the button and staple feeding mechanism of a button attaching machine of the 20 type above referred to, all as hereinafter separately referred to and described and finally claimed.

The drawings accompanying and forming a part of this application illustrate the preferred embodiment of my invention, although it will be understood that my invention includes such variations and modifications of the specific form of my invention 30 illustrated as will be obvious to those skilled in the art to which my invention relates.

In the accompanying drawings: Figure 1 is a view showing my improved button attaching machine in side elevation; Fig. 2 is a view showing the same in front elevation; Fig. 3 is a fragmentary view taken upon a horizontal plane indicated by the line 3—3. Fig. 1, and showing certain staple feeding mechanism forming a part of my machine; Fig. 4 is a similar view showing the parts 40 shown in Fig. 3 in another position; Fig. 5 is a fragmentary view taken upon a vertical plane indicated by the line 5—5, Figs. 3 and 4, and illustrating the operation of the parts, the parts being in the same positions in Figs. 45 3 and 5; Fig. 6 is a similar view, the parts being in the same positions in Figs. 4 and 6; Fig. 7 is a view taken upon a vertical plane indicated by the line 7—7, Fig. 3, and illustrating certain details of the staple feeding mechanism of my machine; Fig. 8 is a view showing various of the parts shown in Fig. 7 in plan; Fig. 9 is a view showing a button receiver which forms a part of my machine in plan; Fig. 9^a is a view showing

a section upon a plane indicated by the line 55 a—a, Fig. 9; Fig. 9^b is a view showing a section upon a plane indicated by the line b—b, Fig. 9; Fig. 10 is a view showing a section upon a vertical plane indicated by the line 10—10, Fig. 9; Fig. 11 is a view taken upon 60 a transverse plane indicated by the line 11—11, Fig. 12, showing the hopper of the staple feeding mechanism of my machine, and the base upon which the same rests; Fig. 12 is a fragmentary view showing a section 65 upon a plane indicated by the line 12—12, Fig. 11; Fig. 13 is a fragmentary view showing the button setting or attaching mechanism of my machine, the same being taken upon a vertical plane, the location and position of which is indicated by the line 13—13, Fig. 3; Fig. 14 is a similar view showing the parts in another position, and illustrating the operation of the parts; Fig. 15 is a similar view showing certain of the parts in section 75 and more in detail; Fig. 16 is a view illustrating a detail of construction provided to facilitate the removal of a plunger forming a part of my machine; Fig. 17 is a view showing a section taken upon a horizontal 80 plane indicated by the line 17—17, Fig. 13; Figs. 18 and 19 are views showing the lower end of the plunger of the button setting mechanism of my machine; and Fig. 20 is a view showing a type of imperforate base 85 button in plan and elevation which may be attached to a garment by my machine.

Referring to the drawings wherein the preferred embodiment of my invention is illustrated, the reference numeral 20 designates a suitable support or pedestal, and 21 designates a suitable frame secured to the upper end of the pedestal and supported thereby, and which frame serves to support the various operating elements of my improved button attaching machine in proper position relative to one another. The pedestal carries a table or tray 22 at its upper end and is provided with a bracket 23 having bearings wherein a shaft 24 is supported and from which the operating elements of my machine are driven through a connecting rod 25 the lower end of which is connected with a crank arm 26 carried by the shaft 24. The shaft 24 is operated from a loose pulley 27 upon the shaft, suitable clutch mechanism not shown being provided whereby the pulley may be operatively connected

with the shaft to drive the machine, which clutch mechanism is operated from a treadle through the rod 28.

Pivotedly supported by the frame 21 of the machine is an oscillating lever 29, one end of which is operatively connected with the connecting rod 25 at 30, while the other end of said lever is operatively connected with a vertically movable button setting plunger 31 through a link 32, said plunger being guided in its movements by a bearing provided for it in the frame 21, as best shown in Fig. 13. The lever in question thus oscillates about an axis at 33, Fig. 1, as the operating shaft 24 is rotated, as will be understood; and the end of said lever is bifurcated to receive the upper end of the link 32 and is cut away to provide circular recesses 34, as best shown in Fig. 16, so that upon the pin 35 being removed the plunger may be moved upward past the end of the lever 29 and withdrawn from its guide or bearing in the frame 21.

The lower end 36 of the plunger 31 is in the form of a sleeve separable from the body portion thereof and in threaded engagement therewith; and 37 is a removable die or heading pin, the upper end of which is dove-tailed and fits within a transverse dove-tailed groove 38 formed in the lower end of the plunger as shown in Figs. 13 and 15, and the lower end of which extends through an opening 39 in the lower end of the sleeve 36, whereby the said die is held in a properly centered position with reference to the plunger 31. The lower end of the die is provided with two transverse grooves 40, Figs. 18 and 19, separated by a central ridge 41, with which grooves the points of a double pronged button attaching staple of the form best shown in Fig. 6 engage when the plunger is moved downward, and whereby the points of the prongs are properly guided past one another and prevented from engaging, as the prongs are bent or curved in the manner illustrated in Fig. 15.

The construction above disclosed obviously permits the button setting plunger to be readily removed from the machine and a new die or heading pin substituted for one worn in use with a minimum amount of dismantling of the machine.

The reference numeral 42 designates an anvil located in line with the plunger 31 and supported from the frame 21 as through a projecting flange 43 in contact with the frame, which anvil is held in place by a nut 44 in engagement with a threaded extension of the anvil, as shown in Figs. 13 and 14, and upon the upper end of which anvil the two-prong staples whereby the buttons are secured to a garment rest preparatory to and while the button is being secured in place.

Surrounding the anvil 42 and guided in its movements thereby is a vertically yieldable jaw carrying member 45, the same being held in its normal uppermost position by a spring 46 and the upward movement thereof being shown as limited by a portion of said member coming into contact with the under side of a staple receiving table 47, to be more fully described hereinafter. The said jaw carrying member is provided with two pairs of pivotally supported jaws, the rear pair 48 serving to guide the fastening staples as they are moved from the table 47 onto the anvil 42, as will be hereinafter explained, and to prevent the staples from taking a position with their prongs lying in a plane at an angle to the direction of movement of the staples; while the front jaws 49 grasp the staples after they have been moved onto the anvil and hold the same in an upright position while a button is being attached to a garment; all as illustrated in Figs. 3 to 6, and 13 of the drawings. Both pairs of jaws are preferably provided with inclined surfaces 50 adjacent their upper ends, and the upper end of the anvil is shown as provided with similar inclined surfaces 51; the purpose of these features being to avoid possible injury to the jaws and anvil as the jaw carrying member 45 and the jaws carried by the same move slightly downward in the normal operation of the machine as will be hereinafter explained, and to permit the overhanging upper ends of the jaws to lie close to the upper end of the anvil without rendering the jaws and jaw carrying member liable to injury when the machine is in use. The operation of the machine, however, is not dependent upon contact of the inclined surfaces upon the anvil and jaws coming into contact with one another; and the feature of supporting the jaws upon a vertically yieldable member is provided in order to avoid the necessity for a close adjustment of the parts, and to avoid injury thereto in the normal operation of the machine. The jaws aforesaid are pivotally supported at their lower ends by pins 52, which pins are held in place by a keeper or latch 53 carried by and rotatable upon a pivot screw 54 and which keeper may engage or be moved off from the heads of the pins to thereby permit the pivoted jaws to be easily removed after the removal of the pins. The pivoted jaws are forced toward one another by means of loop springs 56, 57, the free ends of which rest in recesses formed adjacent the upper ends of the jaws and the loop portions of which springs lie normally beneath the keeper 53, as shown in Fig. 2, and are prevented from rising and getting in the way of the operator by said keeper. When, however, the longer or right hand end of the keeper is swung upward preparatory to removing the

pins and jaws, the springs may be swung upward and easily grasped by the fingers in order to remove them.

From the above it will be obvious that the rear jaws may close independently of the forward jaws; and the said rear jaws will, when the machine is in operation, close to form a guide for the succeeding staple at a time when the forward jaws may be still held apart by the head of the staple, the material of the garment, and the downwardly extending hub of the button, as will be understood from Fig. 14, the rear jaws being made somewhat shorter than the front jaws in order that the garment may not interfere with their closing movement. The rear jaws thus return to the positions which they occupy while a staple is being moved onto the anvil earlier in the cycle of operation of the machine than would be the case if a single pair of jaws were employed; and the staple may be advanced toward the anvil earlier than has heretofore been the case in similar mechanisms, thus insuring that it will be in proper position when the next succeeding button is to be attached to the garment, which is a feature of importance especially in machines designed to operate at high speed.

The reference numeral 58 designates a support or bracket resting upon and suitably secured to the lower portion of the frame 21 and which block serves as a support for various elements of the staple or equivalent fastener feeding mechanism of my machine. The said bracket is provided with an opening adapted to fit over the collar 43 of the anvil and whereby the anvil and the elements of the fastener feeding mechanism carried by said bracket are kept in proper position relative to one another. The under side of the bracket being flat, and the surface of the frame upon which it rests being also flat, the bracket may be easily adjusted about the anvil as a center and made to occupy a proper position relative to the lower end of a supply chute 59 to be hereinafter more specifically described, so that the fastening staples will be properly fed to the staple holding jaws and to the anvil. The bracket 58 supports the fastener receiving table 47 above referred to, which table is provided with a slot 60; and the said bracket is provided with a guide-way 61 located beneath the slot 60 and within which guide-way a reciprocating staple feeding slide 62 operates, said member having an arm 63 extending upwardly through the slot 60 and along the upper surface of the staple receiving table 47. The free end 64 of the arm 63 is adapted to engage successive fastening staples after they pass from the lower end of the staple chute 59 onto the table 47, and to push them from the table onto the upper end of the anvil and between the upper

ends of the staple grasping jaws 49 hereinbefore referred to, as will be understood from Figs. 3 to 6 of the drawings.

The fact that the staple feeding chute 59 is arranged to discharge downward and at an obtuse angle to the path along which the fastening staples move toward the anvil, as will be understood from Figs. 7 and 8, insures that the fastening staples will slide onto the staple receiving table 47 in the same direction as the direction in which they are to be subsequently moved, and with a minimum of retardation and liability to displacement; and that they will be less liable to assume a position which might result in jamming of the staple feeding mechanism as they are advanced toward the anvil and holding jaws than would be the case if the staple chute extended at right angles to the staple receiving table.

The staple feeding slide is provided with a downwardly extending pin 65, and 66 is an oscillating bell-crank lever pivotally secured to the bracket 58 at 67 and one end of which is bifurcated to engage the pin 65. The lever 66 is operated from the oscillating lever 29 by means of a pin 68 operating in an elongated slot 69 formed in an oscillating lever 70 pivotally secured to the frame 21 at 71, which lever has an arm 72 operatively connected with a cross head 73 slideable upon a pitman 74 the other end of which is operatively connected with the bell-crank lever 66 above referred to. A spring 75 surrounds the pitman 74 through which spring motion is transmitted to the slide 62, and which spring will permit the cross-head to move without moving the lever 66 in case a staple gets jammed or caught on its way to the anvil and staple holding jaws; thus avoiding injury to the reciprocating staple feeding slide as will be understood. The bell crank lever 66 is provided with a screw 76 adapted to engage the bracket 58 when the lever is at the end of its movement in the direction which results in movement of the staple feeding slide 62 toward the anvil, to thereby limit the movement of the slide in that direction, as will be understood.

The slotted oscillating lever 70 is provided with a second arm 77 in operative engagement with a pivotally supported lever 78, which lever operates an oscillating staple escapement 79 through a suitable connection 80, and operates also a rotary staple hopper 81 through a suitable connection 82 and suitable ratchet mechanism located beneath the hopper and designated as a whole by the reference character 83. This operating mechanism is not illustrated in detail, as the same forms no part of the invention to which this application relates.

The staple escapement 79 is pivotally secured to the under side of the staple chute 130

59 as by means of a screw 84, and the same is provided with two arms 85, 86 located upon the upper side of the staple chute as best shown in Figs. 7 and 8. The arm 85 has a stop 87 at its lower end adapted, when moved into the position shown in Fig. 7, to engage the lowermost staple and thus arrest the downward movement of the staples in the chute, and to release the lower staple 10 as the arm moves into the position shown in Fig. 8. The second arm 86 of the escapement is provided with a stop 88 adapted to arrest the downward movement of the staples when in the position shown in Fig. 15 8, and with a staple accelerating projection 89 having an inclined edge 90, which edge, as the arm by which said accelerating projection is carried is moved into the position shown in Fig. 8, engages the lowermost 20 staple and gives it a positive push, thus starting the staple toward the staple receiving table with a more rapid motion than would be the case if the force of gravity, alone, was relied upon to move the staple 25 as it is released by the stop 87.

The rotary staple hopper 81, see Figs. 11 and 12, is substantially cylindrical in form, and its lower end is provided with a series of slots 91 adjacent its lower end designed 30 to pick up separate staples from a mass of staples within the hopper, and to discharge them into a space 92 from which they pass into the staple chute 59, all, in accordance with the usual operation of feeding mechanism of the type illustrated. The said hopper is supported upon a base 93, which in turn is supported from the frame 21 by means of a bracket 96, and rotates about a central axle, and, in order to prevent the 40 staple hopper from becoming jammed after the staple chute is full of staples as by reason of staples within the slots 91 failing to fall therefrom, I provide an opening or recess 94 in the base over which the slots 45 91 pass and into which such staples as do not pass into the chute may fall. This opening or recess is cut off from direct communication with the interior of the hopper by reason of the fact that it extends only 50 beneath the slots 91, and not inwardly beyond the slots, from which it follows that the mass of staples within the hopper cannot interfere with or prevent the staples from falling from the slots. The said recess is preferably located adjacent the end 55 of the space 92, so that staples carried to the end of the space may not be caught between the hopper and the base 93, but will fall into the recess, and the recess preferably 60 communicates with the interior of the staple hopper as through a passage 95, so that the staples which fall from the slots return automatically to the interior of the staple hopper.

It will of course be understood that in 65 feeding hoppers of the type employed in my

machine, it is expected that the articles fed which do not pass out of the slots and into the chute, will fall from the slots into the interior of the hopper as the slots move into their highest position, thus avoiding jamming of the hopper. This operation will commonly take place if the hopper is only partially filled. Operators are, however, prone to fill the hopper as full as possible with buttons, staples, or whatever articles 70 are being fed, or at least too full, in which case the articles may be prevented by the mass within the hopper from falling from the slots into the interior thereof, with a resultant tendency to jamming by the articles 75 being carried to the end of the space into which the articles normally pass on their way to the chute and there caught between the hopper and the base upon which it is supported. 80

The feature above referred to of providing for a more positive discharge of such articles as fail to pass into the chute may obviously be used with feeding hoppers designed to feed any articles, whatever, and 85 is used by me in my machine upon both the staple feeding hopper and the button feeding hopper, although the feature in question is illustrated in detail only in connection with and as applied to the staple feeding 90 hopper. 95

The fastening staples after having been released by the escapement 79 as hereinbefore explained, pass from the lower end of the staple chute onto the staple receiving table 47 and rest thereupon in an upright position between a guard 97 formed by one side of the lower end of the staple chute, see Fig. 6 and Fig. 8, and a second guard 98, Figs. 3, 4 and 8 pivotally secured to the bracket 58 at 99, so that said second guard may be swung away from the lower end of the chute in order to permit the removal of a staple should one become caught or jammed in this portion of the machine; the two 100 guards thus forming a groove or raceway 105 along which the staples pass on their way to the anvil. The pivotally supported guard is held in proper position by means of a pin 110 extending therethrough and into a hole 115 in the table 47.

The reference numeral 101, Fig. 1, designates a guard pivotally secured to the lower end of the staple chute 59 and extending over the points of the staples to thereby prevent the garment to which the buttons are attached from coming into contact with the said points. 120

The reference numeral 102 designates a rotary button feeding hopper designed to 125 receive a mass of buttons and to supply the same to a downwardly extending button chute 103, which chute is twisted as shown in the drawings in order that the buttons may be supplied to a button receiver form 130

ing a part of my machine, right side up, in which position they are secured to a garment designated by the numeral 104. This button hopper is supported upon a suitable base 105, which in turn is supported from the frame 21 by means of a suitable bracket. The button hopper rotates about a suitable axle carried by the base, and rotary motion is transmitted to the same from the oscillating lever 29 through a pitman 107 and suitable ratchet mechanism designated as a whole, by the numeral 108, the said ratchet mechanism and the hopper itself, however, not being illustrated in detail as the same form no part of the invention to which this application relates.

The numeral 109 designates an oscillating button escapement pivotally connected with the button chute and designed to release buttons one by one and permit them to pass down the button chute to a button receiver to be next described, which escapement is operated by means of a projection upon the lever 29 which engages therewith, which features, however, form no part of the invention to which this application relates.

The buttons, after having been released by the button escapement, pass from the lower end of the chute into a cup-shaped cavity formed by oppositely located recesses 110 at the outer or free ends of two adjacent co-operating button receiving members 111 suitably supported by a supporting member 112 shown as in the form of an oscillating arm, the rear end of which is pivotally supported from the frame of the machine at 113, the free ends of said members being separable so that a button resting within the cavity formed by the recesses 110 may be forced downward by the plunger 31 and through the bottom of the cavity as the ends of the arms move apart from one another, the said members thus forming a button receiver designed to receive a button from the lower end of the chute and to hold the same preparatory to its being secured to a garment. The said button receiving members are shown as provided each with a curved recess which bears upon a stud 114 having a flange 115 at its upper end, as shown in Fig. 10, and a spring 116 is provided for holding the members together and in proper positions, which spring, however, permits the free ends of the members to move apart about the stud as a center. The arm 112 carries also a double lobed cam 117 secured in place by a screw 118 and the lobes of which cam may be made to act, as by rotating the same upon the screw 118 by means of a handle 119, upon a surface of each of the button receiving members 111 to thereby force the free outer ends of the members apart and thus permit a button within the cavity aforesaid, and which is not to be se-

cured to a garment, to fall from the button receiver. A stop 120 is provided for limiting the upward movement of the arm 112 so that the cavity in the button receiver will be properly located with reference to the lower end of the button chute, and 121 is a spring-pressed member which acts in an upward direction against the under side of the arm to thereby hold it in its normal uppermost position and the cavity aforesaid close to the lower end of the button chute.

The inner surface of the cup-shaped cavity formed by the recesses 110 is of a conformation to permit the buttons to pass into it with a minimum of friction and consequent retardation and to at the same time reduce to a minimum oscillating or rocking motion of the button after it has passed into the cavity, to which end the rear portions 122 of the recesses are conical surfaces, while the front portions 123 are plane surfaces extending longitudinally of the button receiver and inclined toward one another, so that the lower portions of said plane surfaces are closer together than the upper portions. From this construction it follows that the advancing edge of a button as it passes into the cavity will engage the inclined surfaces 123 at two points only, and because of the slight amount of friction between the button and these surfaces, the button will slide into the cavity with but slight retardation of its motion, during which movement its front portion of the button will be raised and the button swung into a horizontal position, as will be understood. When the advancing edge of the button reaches the forward vertical wall 124 of the cavity, the button will have been brought into a substantially level or horizontal position and the rear or following edge thereof will fall into the cavity and will contact with the conical portions 122 thereof throughout or along nearly one-half of its periphery, thus introducing a considerable amount of friction between the button and the inner surface of the cavity which will bring the button to a position of rest immediately and prevent it from rocking upon two points of support as has been the case in button receivers in which inclined surfaces similar to the surface 123 formed the entire bottom wall of the button receiving cavity. On the other hand, if the button receiving cavity were conical throughout its entire extent, the advancing edge of the button would contact therewith along a considerable portion of the edge, and the resulting friction would tend to prevent the button from coming into a horizontal or level position, thus interfering with the operation of the machine.

The button receiver above referred to and described will obviously move up and down in the operation of the machine, for which

reason I refer to it as a vertically movable button receiver; and, while I have shown the said receiver as carried by an arm which is pivotally connected with the frame of the machine, it will be understood that my invention includes a button receiver having an up and down movement, together with the other elements and features enumerated in the claims in combination therewith, irrespective of the particular mechanism employed for permitting such vertical or up and down movement.

The arm 112 is provided with a lifting member 125 upon its under side and which member is shown as loosely supported in a slot formed in the end of said arm as by means of a transversely extending pin 126. The forward or free end of this arm lies close to the hub of the button after it has been attached to the garment, and the purpose of said member is to pull or to assist in pulling the attaching staple and the hub of the button from between the staple grasping jaws 49, after a button has been secured in place, to thereby insure that the said jaws will close as early as possible in the cycle of operation of the machine and thus permit the succeeding attaching staple to be advanced onto the anvil earlier than would be the case if the closing of said jaws was delayed.

In using my improved button attaching machine to attach buttons to a garment, the edge of the garment is placed beneath the button receiver and over the anvil and jaws hereinbefore referred to as shown in Fig. 13. Thereupon, (it being assumed that a staple has been placed in position upon the anvil 42 between the staple holding jaws 49, and a button supplied to the button receiver, both as hereinbefore explained,) the plunger 31 is moved downward until its lower end enters the button receiving cavity of the button receiver and engages the button, after which the button receiver moves downward with the plunger. The downward movement of the button receiver is finally arrested as the edge of the garment is caught between its lower surface and the upper surfaces of the staple holding jaws 49, after which the button is forced along the inclined wall of the button receiving cavity and through the bottom thereof as the free ends of the button receiving members 111 move apart from one another. In the meantime, however, the points of the fastening staple have been driven through the material of the garment and through the base of the button, and, as the plunger continues to move downward, the lower end of the hub of the button is forced between the staple holding jaws thus separating them in the manner illustrated in Fig. 14 of the drawings; the prongs being curled or riveted, as illustrated in Fig. 15, as the

plunger reaches its lowermost position. During this operation the spring 46 obviously permits the jaw carrying member 45 and the jaws to move downward, if necessary, as the button is attached to the garment. As the plunger subsequently moves upward the button receiver is forced upward by the spring-pressed abutment 121 and the lifting member 125 engages the under side of the top plate or flange of the button and lifts the button and garment, thereby pulling the head of the attaching staple from between the jaws 49 and permitting them to close early in the cycle of operation of the machine. The button, obviously now lies below the button receiver so that the garment may be readily moved into a position to receive a second button, and, as the parts finally return to their initial position shown in Fig. 13, a second staple and button are placed in position to be attached to the garment upon the next downward movement of the plunger.

Having thus described and explained my invention, I claim and desire to secure by Letters Patent:—

1. In a button attaching machine, a suitable base, a hollow rotary feeding hopper cylindrical in form supported upon said base and the lower end of which is provided with a series of slots the lower ends of which slots move adjacent the surface of said base, said base having an opening over which said slots pass, and which opening terminates adjacent the inner ends of said slots and a supply chute independent of said opening and adjacent which said slots move as said hopper is rotated.

2. In a button attaching machine, a suitable base, a hollow rotary feeding hopper cylindrical in form supported upon said base and the lower end of which is provided with a series of slots, the lower ends of which slots move adjacent the surface of said base, said base having an opening over which said slots pass, and which opening terminates adjacent the inner ends of said slots, said opening being placed in communication with the interior of said hopper through a suitable passage.

3. In a button attaching machine, a suitable base, a hollow rotary feeding hopper cylindrical in form supported upon said base and the lower end of which is provided with a series of slots, the lower ends of which slots move adjacent the surface of said base, said base having an opening over which said slots pass, and which opening terminates adjacent the inner ends of said slots, said opening being placed in communication with the interior of said hopper through a suitable passage, and which passage discharges into said hopper in the direction in which the same rotates.

4. In a button attaching machine, a suit-

- able base; a supply chute; a hollow rotary feeding hopper supported upon said base and having a series of slots through which articles to be fed may pass to said chute, 5 said base having an opening independent of and located in advance of said chute and past which said slots move, and into which opening articles may pass from said slots.
5. In a button attaching machine, a suitable base; a supply chute; a hollow rotary feeding hopper cylindrical in form, supported upon said base and having a series of slots at the end thereof adjacent said base and which slots move adjacent said chute, 10 so that articles may pass from said slots into said chute, said base having an opening independent of and located in advance of said chute, and over which openings said slots pass.
10. 6. In a button attaching machine, button fastener feeding mechanism comprising a receiving table; two parallel guides resting upon said table and spaced apart to thereby provide a groove between them; a reciprocating slide moving between said guides and adapted to move fasteners toward an anvil; means for operating said slide; and a chute adapted to supply fasteners to said groove.
7. In a button attaching machine, button fastener feeding mechanism comprising a receiving table; two parallel guides resting upon said table and spaced apart to thereby provide a groove between them and one of which guides is pivotally supported so as to 30 swing about an axis at right angle to said table; a reciprocating slide moving between said guides and adapted to move fasteners toward an anvil; means for operating said slide; and a chute adapted to supply fasteners to said groove and which chute discharges downward and at an angle to the direction in which the fasteners are moved by said slide.
8. In a button attaching machine, button fastener feeding mechanism comprising a 35 downwardly extending chute; means for arresting downward movement of the fasten-
- ers in said chute and for releasing separate fasteners in succession; and means independent of said fastener arresting means for accelerating the movement of each separate fastener as it is released. 50
9. In a button attaching machine, button fastener feeding mechanism comprising a downwardly extending chute; means for arresting downward movement of the fasteners in said chute and for releasing separate fasteners in succession; and a reciprocating fastener accelerating member independent of said arresting means and arranged to engage each separate fastener as it is released, 55 the portion of said member which engages the fasteners being inclined with reference to the direction in which the fasteners are moved. 60
10. In a button attaching machine, button fastener feeding mechanism comprising a downwardly extending chute; a reciprocating escapement carried by said chute and arranged to release separate fasteners in 65 succession; and an accelerating projection carried by said escapement and arranged to engage each separate fastener as it is released by said escapement, the portion of said projection which engages the fasteners 70 being inclined with reference to the direction in which the fasteners are moved. 75
11. In a button attaching machine, a hollow rotary feeding hopper having a series of slots, means for supporting and for rotating 80 said hopper, a chute the upper end of which is located adjacent the path of movement of said slots, and a member having an opening independent of and located in advance of said chute and past which opening said slots 85 move as said hopper is rotated.

Signed at Waterbury in the county of New Haven and State of Connecticut this 31st day of Dec. A. D. 1912.

FRANKLIN R. WHITE.
